UNITED STATES PATENT OFFICE.

CHARLES THOMAS LEE, OF BLAUVELT, NEW YORK.

CUSPIDOR-LIFTER.

1,113,025.

Patented Oct. 6, 1914.

Application filed November 12, 1913. Serial No. 800,583.

To all whom it may concern:

Be it known that I, CHARLES THOMAS LEE, a citizen of the United States, residing at Blauvelt, in the county of Rockland and State of New York, have invented new and useful Improvements in Cuspidor-Lifters, of which the following is a specification.

The general object of this invention is to obviate the necessity of placing the hands on a cuspidor or the like, whenever it is necessary to move around or clean the cuspidor.

It is a well-known fact that a large percentage of contagious diseases are spread by expectoration, and as approximately all office buildings and public structures contain cuspidors, it is obvious that these cuspidors are more or less contaminated; therefore, it is very unsanitary for the employees of such buildings to be handling the cuspidors in this condition.

To attain the object in view the invention consists of a jaw portion for engaging with the cuspidor and a handle for carrying the said jaw.

Other objects will appear and be better understood from that embodiment of my invention of which the following is a specification, reference being had to the accompanying drawings forming part hereof, in which:—

Figure 1 is a perspective view of the device applied to a usual cuspidor cover. Fig. 2 is a perspective view of the device. Fig. 3 is an elevational view of the device applied to the bowl of a cuspidor similar to that shown in Fig. 1. Fig. 4 is an elevational view of the device applied to another style of cuspidor.

The device as shown in the drawings, consists of a body portion *a* and a jaw-member *b* carried by the said body portion.

The part *a* may be formed of wood or of some suitable metal of light weight, and may be cylindrical in cross section; its length may be of such size that when placed in position on a cuspidor, it will be within easy reach of the operator's hands, so that stooping will be unnecessary. Spaced at various intervals on the body *a* and in vertical alinement, are a plurality of eyelets *c* by which means is carried the securing member *b*.

The member *b* consists of a rod *d* which is journaled in the eyelets, and which is provided with a crank handle *e* at the upper

end. A foot *f* is secured to the lower end of the rod and is positioned beyond the end *g* of the body portion *a*. This admits of the foot being swung around by the handle *e*, under the end *g*. Adjacent to the handle *e* an annular collar *h* is secured to the rod *d*; between the collar *h* and the uppermost eyelet *c* a coil spring *i* is wound around the rod; and as the rod is plunged downwardly the spring is tensioned between the eyelet and the collar *h*. It will be seen that upon the handle *e* being plunged downwardly against the action of the spring and the foot *f* swung around in position under the lower end *g* of the body, the action of the spring will be to force the foot upwardly and in contact with the said lower end of the body portion or handle *e*.

Positioned at the lower portion of the part *a* and in alinement therewith, is an arm *j*, which is bent as at *k* so as to be in spaced relation with the said part *a*. This arm is flared outwardly at the end *l* and is adapted to coöperate with the part *a* in fitting over the side of the cuspidor *c*. As shown in Figs. 2 and 3 the foot *f* is of sufficient length to contact with the arm *j*.

In operation, a porter or the like wishing to remove the cover *c* of the cuspidor, places *a* thereon the device so that the end *g* of the body, will stand on the upper face of the cover. The handle is then plunged downwardly as above described and the foot *f* swung into the opening *k* of the cover and in under the lower face of the same. The tension of the spring will force the foot upwardly to the position shown in dotted lines in Fig. 1, and the cover, being secured between the foot and the end *g* of the body *a* by the action of the spring, can be lifted by the body portion or upright *a*, and placed in the position shown in Fig. 3 if so desired. After removing the cover, the above mentioned operation is reversed and the device *a* is disengaged therefrom. It can then be used for carrying the bowl *c* as shown in Fig. 3. For doing this, the device is positioned so that the side of the cuspidor is fitted between the arm *j* and the body *a*. The foot is swung around under the bottom of the cuspidor and it can be carried or moved about as desired. For use on a different form of cuspidor shown in Fig. 4, the device is positioned so that the lip *k* is between the arm *j* and part *a*, as described for Fig. 3, and the foot is swung against the

110

inner face of the cuspidor; by virtue of the rod being secured to the end of the foot, the foot will swing eccentrically when the rod is rotated, thus it will bind against the inner face of the cuspidor, and coöperate with the arm 13 for holding the cuspidor.

The device can be used for holding the cuspidors while being cleaned, and can then be plunged into a disinfecting bath. Owing 10 to the sanitary value of the invention it can be used not only with cuspidors but for any purpose when such opportunity occurs.

What is claimed as new is:

A lifter comprising a body, an arm attached to one side of the body and having

an end portion spaced from the end thereof, said spaced end portion of the arm being approximately parallel with the adjacent end portion of the body and a rod rotatably mounted at the opposite side of the body 20 and having an angularly disposed foot adapted to be swung under the end of the body and the arm carried thereby.

In testimony whereof I affix my signature in presence of two witnesses.

CHARLES THOMAS LEE.
